UNITED STATES PATENT OFFICE.

CHARLES GOODYEAR, JR., OF NEW YORK, N. Y.

IMPROVED LACING FOR BOOTS AND SHOES.

Specification forming part of Letters Patent No. 55,852, dated June 26, 1866.

To all whom it may concern:

Be it known that I, CHARLES GOODYEAR, Jr., of New York, in the county and State of New York, have invented certain new and useful Improvements in Lacing-Eyes for Boots and Shoes and other Wearing-Apparel; and I hereby declare the following to be a full, clear, and exact description of the same.

This invention relates to method of lacing or lacing device for which Letters Patent of the United States were issued to Jacob Autenreith on the 6th day of January, 1863, and re-issued February 20, 1866, the metallic lacing-eyelet being arranged so that the lacing-cord runs through the same without traversing the leather of the shoe. These lacing-eyes, as heretofore constructed, were arranged either on the upper, as shown by the said Autenreith, or on the edge of the welt or binding; and my invention particularly relates to the latter; and its object is to make and apply these lacing-eyes at less cost of labor and material than this could be done heretofore, and thus to cheapen the manufacture of shoes with lacing-eyelets such as hereinbefore referred to. To this effect I form the lacing-eyelets—*i. e.*, the lacing-eye proper, shank, and loop—of a single piece of wire by bending the ends into eyes, so as to stand at right angles to each other. One of these eyes constitutes the lacing-eye proper, while the other is the eye whereby the said lacing-eye is fastened, by means of a rivet, to the shoe, and which, in contradistinction to the lacing-eye, I call the “loop” or “rivet” eye. This lacing device is applied to the shoe by inserting the loop and shank between the two layers or thicknesses of the welt, so that the lacing-eye only shall project from the edge of and at right angles to the upper.

My invention therefore consists in inserting and fastening between two layers of leather the lacing device, so that the lacing-eye alone shall protrude from the upper and at the edge of the part to be laced; also, in forming the lacing device of a single piece of wire, the ends of which are shaped or bent into eyes; also, in the employment, in combination with such lacing-eye, of a rivet traversing either or both sheets of leather between which the lacer is confined; also, in the combination, with such lacing and fastening device, of a folded

leather welt or upper, the edge having incisions at equal distances apart, and at right angles to the folded edge, for the passage through them of the lacing-eyes.

To enable others to make and use my invention, I shall now proceed to describe the manner in which the same is or may be carried into effect by reference to the drawings, in which—

Figure 1 is a perspective view of a shoe or boot to which my improvement is applied. Fig. 2 is a perspective view of the folded edge or welt of the shoe and lacing-eyes. The former, together with the rivet-head, is shown in red ink. The lacing-eye proper is represented in black lines. Fig. 3 is a similar view, a portion of the upper sheet of leather being removed to exhibit the manner in which the lacers are arranged between the two sheets of leather. Fig. 4 is a transverse section, on *a b* in Fig. 5, of the welt on an enlarged scale. Figs. 5 and 6 are front and rear elevations of the same.

In the said drawings the lacing-eyelet is shown to be composed of three parts, *g*, *s*, and *m*, *g* being the lacing-eye proper, *s* the shank, and *m* the eye, whereby the device is fastened to the shoe or boot, or to a binding welt or strip of leather or other material making part of the shoe or boot to which it is attached. These three parts are composed of a single wire, both ends of which are bent to form the lacing-eye *g* on the one end and the rivet-eye *m* on the other. The intermediate piece of wire, which I call the “shank” or “link,” *s*, is of sufficient length to allow the rivet to be placed at a distance from the edge of the part to be laced to insure strength without materially interfering with the flexibility or limberness of the upper.

The two eyes, it will be seen, are formed on the shank at right angles to each other, so that when one of the eyes is placed flat or in a position parallel with the sheets of leather to which it is secured the other will be at right angles thereto, and thus the eyes are situate in planes perpendicular to the general surface of the upper.

The manner in which these lacing-eyelets are attached is shown in the annexed drawings.

The open parts which are to be united by lacing are composed of two sheets of leather, or of the upper and lining, or of a single thick-

ness, but provided with a welt or binding. The lacing-eyelet is let in or inserted between such two thicknesses of leather, or in the fold of the binding or welt, and secured in place by a rivet, *p*, traversing the eye *m*, and, as shown, both thicknesses of leather, or it may traverse but one thickness of leather. The latter plan need not interfere with giving the shoe or boot ornamental buttons or studs produced by the heads of rivets, for the lacing-eyelet may be clinched to the upper-leather only. The other thickness of leather may lap under and act as a protecting lining against the projecting head.

If the eyelet is used in connection with a folded strip or welt or binding, then I prefer to make transverse incisions *w*, through which the heads or lacing-eyes proper, *g*, of the eyelet are passed and adjusted previous to being secured by the rivets.

It will be understood that this mode of making and attaching eyelets is applicable to shoes or boots of any kind of material other than leather, and also to other descriptions of wearing-apparel.

Having thus described my invention and the manner in which the same is or may be carried into effect, what I claim as my invention is—

1. The method herein described of applying lacing-eyelets to boots and shoes by inserting

and fastening the same in between two sheets or thicknesses of leather in such manner that the lacing-eye alone shall protrude at and at right angles to the edge of said leather, substantially as herein shown and set forth.

2. The lacing-eyelet constructed substantially as herein shown and described—that is to say, forming the same of a single piece of wire the ends of which are bent into eyes standing at right angles to each other, substantially as herein set forth.

3. In combination with eyelets constructed substantially as herein described, the employment of rivets traversing one of the eyes of the lacer and either or both thicknesses of leather between which the said lacer is confined.

4. The employment, in combination with lacers and rivets, as hereinbefore described, of a folded leather welt, binding, or equivalent, the folded edge of which having at right angles to it incisions through which the lacing-eyes protrude, substantially as herein shown and described.

In testimony whereof I have signed my name to this specification before two subscribing witnesses.

CHAS. GOODYEAR, JR.
